CLAIM

The ornamental design for a wheel or wheel cover, as shown and described.

DESCRIPTION

FIG. 1 is a front view of a wheel or wheel cover according to our novel design; and,

FIG. 2 is a perspective view thereof.

The broken line showing of the rear portion of the wheel rim and the central hub area is included for the purpose of illustrating environment and form no part of the claimed design.

1 Claim, 1 Drawing Sheet

FIG. 1

FIG. 2
